HUBERT HENRY AND JAMES DAILEY DAY, OF BRADFORD, ENGLAND

OYSTER OR LIKE OPENING APPARATUS

Application filed February 25, 1930, Serial No. 431,076, and in Great Britain March 18, 1929.

This invention relates to an apparatus for the opening of oysters or the like.

To open oysters rapidly and without damage thereto is a matter requiring considerable skill and the number of persons skilled in the art is not great. As a result much time and incidentally many oysters are wasted by unskilled treatment.

Our object is to arrange and construct an oyster or like opening apparatus which is easy to manipulate and which will not damage the oyster.

Broadly the apparatus will comprise a holder for the oyster shell which holder will be flexibly carried or hinged in connection with the apparatus, and a knife which may be moved towards the shell holder, or the knife may be a fixture and the shell holder be drawn towards the knife.

Adjustability will be provided with respect to such parts as require it.

The advantages of the invention as well as the operation will be readily comprehended from the following detailed description of the drawings wherein,

Fig. 1 represents a general view of a machine constructed according to our invention.

Fig. 2 represents an underside view of a knife.

Fig. 3 represents a side view of a knife and

Fig. 4 represents a transverse section of the oyster carrier taken on line *a*—*b* of Fig. 1.

In the drawings we have shown a form of machine adapted to be clamped to a table or the like, but it will be obvious the machine may be mounted, supported and operated in other ways, for example we may find it desirable to employ a fixed knife and draw the shell towards the knife and not the opposite

as hereinafter described. A represents a bracket of suitable form adapted to be clamped to a table or like by clamp members *A*' and *A*². The bracket A is provided with a bearing B for a threaded shaft S, and a

handle H is provided for turning such shaft, and in some forms the outer end of the shaft may be supported on a bearing carried by the outer part *A*³ of the bracket A which is of a somewhat semi-circular open cross section

and carries or has formed on its arms, slides

*A*⁴, within which a knife or like K operates.

The knife K carries a boss K' from which it is easily removable, which boss engages the shaft S and on turning of such shaft, a pin or like S' in the boss K' engages the spiral groove S² of the shaft and so causes the knife to travel in its slides. This knife has a somewhat rounded point K² and its edge K³ is formed with a slightly downward trend from the point, and we prefer to add guides G to the underside of the knife as in Figs. 2 and 3 which have a tendency to prevent the under face of the knife from, as it were, gathering the oyster and so tending to break same and at the same time serve to press the lower shell downwards.

The oyster or like is mounted in a holder somewhat U-shaped in formation with its outer portion H' slightly dished. In some forms a gap may be left in the said dished edge for the knife point to pass into. The holder is pivotally attached to arms C preferably slightly cranked as at C' which are pivoted as at C² to the part *A*³ of the bracket and the holder is provided with a cross bar H² suitably curved as in Fig. 4.

When it is desired to set the holder for varying sized oysters or the like, the arms H³ may have several holes such as H⁴ therein and the cross bar H² acts as the pivot and may be secured in the desired holes by means of a nut or like H⁵ as in Fig. 4, which shows a section through the pivot portion on line *a*—*b* of Fig. 1.

An extra foot A⁵ shown dotted in Fig. 1 may be added to the bracket A to give extra stability if required.

We may add to the machine suitable wiping devices for the edges of the knife as it is operated.

The machine as a whole is constructed in such wise and from such material that it may be readily cleaned and sterilized.

The reason for mounting the shell holder or carrier on flexible or double hinged connections is that there is a great variety in the thickness of shells and disposition of the hinge, and to cause the knife to engage the hinge of the shells it may be necessary to give the holder a certain amount of manipu-

100

lation such as by raising same somewhat. Once the knife has entered the hinge of the shell no further manipulation of the carrier is needed and the carrier may assume a position in alignment with the knife or substantially so but slightly below its plane.

The oyster or the like, having been placed in its holder, with the hinge part to the knife, and the knife moved to engage the hinge portion, the knife is moved forward in its slide and the holder being relatively stationary, the top shell is detached and the upper muscle, connected to the shell, severed and the knife may pass to the limit of its travel and so remove the top shell, leaving the lower shell containing the oyster in the holder.

The apparatus is sure in its action and with a little practice may be operated rapidly and no damage ensue to the oyster.

We have shown and described what we believe to be the simplest and best form of our invention, but certain modifications may be made in the construction without, however, departing from the spirit of our invention,

What we claim is,

1. A device of the character described, comprising in combination, a supporting member, a knife mounted for reciprocatory movement on said member, a pair of arms pivotally connected to the support respectively at opposite sides of said knife, and an oyster supporting member pivoted to said arms and adapted to occupy an angular position different from that of the arms with relation to the path of the knife.

2. A device of the character described, comprising in combination, a supporting member, a knife mounted for reciprocatory movement on said member, a pair of arms pivotally connected to the support respectively at opposite sides of said knife, and an oyster supporting member adjustably pivoted to said arms and adapted to occupy different angular positions with relation to the path of the knife and to said arms.

3. A device of the character described, comprising in combination, a supporting member, a knife mounted for reciprocatory movement on said member, a pair of arms pivotally connected to the support respectively at opposite sides of said knife, and a curved member pivotally connected at its opposite ends to the respective arms whereby the curved member and arms are adapted to occupy different angular positions with respect to the path of travel of the knife.

In testimony whereof we have signed our names to this specification.

HUBERT HENRY.
JAMES DAILEY DAY.
